DESIGN FOR A DRAWING INSTRUMENT

Lawrence A. Matson, Dayton, Ohio

Application April 13, 1945, Serial No. 118,387

Term of patent 14 years

(Cl. D52—1)

To all whom it may concern:

Be it known that I, Lawrence A. Matson, a citizen of the United States, residing at Dayton, in the county of Montgomery and State of Ohio, have invented a new, original, and ornamental Design for a Drawing Instrument, of which the following is a specification, reference being had to the accompanying drawing, forming a part thereof,

In the drawing, Figure 1 is a top plan view of a drawing instrument, showing my new design. Figure 2 is a side elevational view.

I claim:

The ornamental design for a drawing instrument, as shown.

LAWRENCE A. MATSON.
